UNITED STATES PATENT OFFICE

ALBERT T. MCCANLIS, OF BROOKLYN, NEW YORK

AWNING

Application filed October 19, 1931. Serial No. 569,756.

The object of this invention is to provide an awning of simple construction which may be easily operated and in which the awning fabric will be held taut when the awning is lowered and will automatically fold flat against the side of the building as the awning is raised. Another object of the invention is to provide means whereby the awning may be easily operated without the provision of the usual ropes and pulleys and will be positively held in either the raised or the lowered position. Another object of the invention is to provide means whereby the awning may be easily hung when its use is desired, or dismounted, when its use is no longer considered necessary. Other objects of the invention will appear incidentally in the course of the following description, and the invention resides in certain novel features which will be hereinafter first fully described and then more particularly defined in the appended claims.

In the accompanying drawings,

Figure 1 is a perspective view of an awning embodying the invention and in its lowered position.

Fig. 2 is a vertical section showing the awning lowered in full lines and raised in dotted lines,

Fig. 3 is a front elevation of a portion of the awning showing the same in its fully raised position,

Fig. 4 is a vertical section on the line 4-4 of Fig. 3,

Fig. 5 is an enlarged detail view of the locking device shown in Fig. 2,

Fig. 6 is an enlarged detail horizontal section on the line 6-6 of Fig. 5,

Fig. 7 is a perspective view showing the several parts of the locking mechanism disassembled but in their proper relative positions,

Fig. 8 is an enlarged detail section of the lower portion of the awning,

Fig. 9 is a perspective view showing a variation,

Fig. 10 is an enlarged detail section on the line 10-10 of Fig. 9,

Fig. 11 is an enlarged perspective view of the operating and holding device shown in Fig. 9,

Fig. 12 is a detail perspective view of a portion of the frame-holding member illustrated in Fig. 11,

The awning of the present invention is especially adapted for use upon windows having screens and may be employed whether the screen is on the outside of the window or on the inside. The form of the invention illustrated in Figs. 1 to 7 is especially adapted to use upon windows having outside screens and, in said figures, the reference numeral 1 indicates a portion of a side of a house or other building, the numeral 2 indicates a window frame and the numeral 3 indicates a screen which is secured upon the outside of the window. In carrying out the present invention, a series of hooks 4 is secured in the screen frame, across the top of the same, and at the top of the awning is provided a suspending rod 5 formed into eyes 6, at intervals in its length, which are adapted to engage over the hooks 4 and thereby suspend the awning, as shown and as will be understood. The awning fabric 7 may be canvas or any of the materials ordinarily employed in awnings and may be ornamented according to the taste of the owner. A hem 8 is formed along the upper end edge of the awning fabric and receives the suspending rod 5, openings being formed through the fold of the hem at intervals corresponding to the spacing of the eyes 6 so that the said eyes may project through the hem in order to engage the suspending hooks 4. Near the lower end of the fabric, a fold 9 is formed transversely thereof to encircle the outer cross portion 10 of a U-shaped frame, the side members 11 of which pass to the stiles of the screen

frame and enter openings therein to be pivotally supported. The lower end portion of the awning fabric extends below the fold 9 and may be scalloped or otherwise finished 5 in order to provide a somewhat ornamental flap 12 as a finish for the awning. Above the fold 9, the awning is provided with stud and socket snap fasteners, indicated at 13, in any desired number, whereby the inner exten- 10 sion 14 of the fold 9 may be detachably held to the main portion of the awning, above the member 10, so that, while the awning fabric will be held taut by the frame, and will follow the movements of the same, in 15 raising or lowering, it may be easily detached from the frame when repairs or replacements are necessary.

As stated, the side members of the awning frame are extended into the stiles of the 20 screen frame and these stiles are provided with vertically extending recesses 15 in their outer sides to accommodate the side members of the frame, when the frame is raised. The inner extremities of the side members 11 are 25 turned at right angles to form journals 16 rotatably fitting in openings provided therefor through the screen frame stiles, as will be understood, and formed or secured upon the journals are heads or disks 17 which are 30 disposed close against the inner sides of the screen frame and are provided with circumferentially spaced radial shoulders 18 defining a recess in which a stud 19, on the operating handle 20, may play. The common 35 expedient of fitting a bushing in the opening or bearing to receive the journal and minimize wear may be adopted, if desired, and this arrangement has the further advantage that if the stile should swell the journal would 40 remain free to rotate. The handle 20 is located adjacent and at the inner side of the disk or enlargement 17 and has a hub member 21 which encircles an annular flange 22 on the side of the disk 17 and may rotate 45 about the same. The extremity of the journal 16 is threaded, as shown at 23, and on the side of the hub 21 is formed or secured a nut 24 which will engage the threaded extremity of 50 the journal and will tend to ride along the same. Spaced outwardly from the hub 21 and the stud 19, a second stud 25 is provided on the side of the handle 20 and this stud 25 is adapted to engage a holding device provided on the screen stile whereby to lock the 55 handle in either the raised or the lowered position. This holding device consists of a base plate or bracket 26 which is secured upon the corner of the stile, one of said brackets being provided above the journal and another be- 60 low the journal with the journal midway the brackets. At its inner end, the bracket 26 is doubled upon itself, as shown at 27, to form a lap or socket in which may be received one 65 end of a resilient latch plate 28, the engaged extremity of the latch plate being riveted or

otherwise firmly secured to the base plate or bracket. The free end of the latch plate is deflected, as clearly shown in Figs. 6 and 7, so that a beveled or obliquely disposed surface is presented to the stud 25 as it rides on the 70 plate and the plate will be thereby pushed to one side, as shown in Fig. 6, in order that the stud may ride along the latch plate and engage the opening 29 provided therein. When the stud 25 reaches a position in alignment with the opening 29, the latch plate immediately springs into engagement with the stud so that the handle will be held in the set position. It will thus be seen that the handle will be firmly held in either a raised or low- 75 ered position and it may be noted also, by reference to Fig. 2, that the handle will be held in a vertical position whether it is raised or lowered and, in operation, will be swung through one-half a revolution. The awning 80 frame 11, in its lowered position, extends horizontally outwardly from the screen frame or the side of the building and in its raised position will extend substantially vertically against the side of the building so that it 85 will move through only one-fourth of a revolution and, in order to accommodate this difference in movement between the handle and the frame, the stud 19 and the spaced shoulders 18 are provided. Assuming the awning 90 to be lowered, as shown in Fig. 2, the stud 19 will be in engagement with the upper shoulder 18 which extends vertically. When the awning is to be raised, the handle will be 95 swung downwardly through one-quarter of a revolution before it imparts any movement to the awning frame and, at the end of this quarter turn, the stud 19 will engage the lower shoulder 18 which, at this time, extends horizontally, and the continued movement of the 100 handle will then impart an upward swinging movement to the awning frame, as will be understood. Of course, a reverse action occurs when the awning is lowered. Thus the handle in either position will be within the 105 lines of the stile and is not apt to be accidentally released.

A swinging folder or auxiliary frame 30 is mounted on the cross bar 10 of the awning frame, to swing about the same, and said auxiliary frame consists of a bail provided in its end or side members with kinks or bends 31 which engage the cross bar 10, as shown in Figs. 1, 2 and 4, and may rock thereon, said kinks or bends being housed 110 within the fold 9, formed in the awning, and being held in engagement with the cross bar thereby. The ends of the auxiliary frame extend through the fold and carry weights 32 which may be given an ornamental configuration and tend constantly to assume a vertical pendent position. When the awning is lowered, the force of gravity acting on these pendent extensions tends constantly to swing the same to the vertical position but is re- 115 120 125

sisted by the engagement of the major portion of the frame with the underside of the awning fabric, as shown in Figs. 1 and 2, but the weight of the auxiliary frame, added to the main awning frame, holds the awning taut so that it will cover the window to its fullest extent and thereby give the desired shade. As the awning frame swings upwardly when the awning is to be raised, the fabric 7 tends to sag between the cross bar 10 of the awning frame and the suspension hooks 4, as will be evident upon reference to Fig. 4. This sagging of the awning fabric relieves the tension upon the upper portion of the auxiliary frame 30 and, consequently, said frame swings toward the vertical and assumes the upright position, shown by the dotted lines in Fig. 2, thereby forming a fold in the awning so that, as the awning frame reaches its uppermost position, the awning will be neatly folded at the top of the window, as shown in Fig. 4.

When the window is not provided with a screen, or is provided with an inside screen, the mounting, shown in Figs. 9 to 12, will preferably be employed. This mounting includes rightangular brackets 33 which are secured upon the outside portions of the stiles of the window frame and are provided with boxes or sleeves 34 constituting bearings for the journals 16 of the awning frame. To the outer end of each box 34 is secured a locking plate 35, which is conveniently of the semi-circular form shown most clearly in Fig. 12, and upon its outer face is provided with radial grooves 36 in which the adjacent side member 11 of the awning frame may be engaged so that the frame will be held in either its raised or lowered position. It will be noted that two of the vertically extending grooves are provided, thus permitting the locking plate 35 to be used at either the right or the left side of the window. The operating handle 20 is provided and rotates upon the hub extension 22 of the disk 17 in the same manner as in the first-described form and the nut 24 rides upon the threaded end of the journal so that the journal will be drawn endwise through the bearing box 34 and, consequently, the side member 11 will be drawn into engagement with the proper groove 36. In this form of the invention, the resilient latch plates 28 will be dispensed with and the locking of the awning in its raised position will be accomplished by the engagement of the awning frame with a groove 36, as stated. When the awning is raised, the nut 24 will have been caused to move away from the box 34 and the disk 17, but it may be manually turned so as to effect the re-engagement of the awning frame in a holding groove.

From the foregoing description, taken in connection with the accompanying drawings, it will be seen that I have provided an

exceedingly simple and inexpensive awning which may be easily operated and readily dismounted when its use is to be discontinued and just as easily suspended in place when its use is desired. The usual ropes and pulleys 70 are dispensed with and the awning is positively held in its raised position and, when it is raised, will be automatically folded flat against the side of the building.

Having thus described the invention, I claim,

1. An awning comprising a sheet of fabric, means for suspending said sheet at its upper end, an awning frame engaged with the lower end portion of the sheet of fabric, means for 80 pivotally mounting the awning frame at the sides of an opening to be shaded, and an auxiliary frame rockingly mounted on the awning frame to engage the underside of the sheet of fabric and fold the same as the 85 awning is raised.

2. An awning comprising a sheet of fabric, means at the upper end of the sheet for suspending the same, an awning frame engaged with the lower end portion of the sheet of 90 fabric and pivotally mounted at the sides of an opening over which the awning is to extend, and an auxiliary frame carried by the awning frame and mounted to rock thereon and having its major portion bearing 95 against the inner side of the sheet of fabric and having extensions depending below the awning frame whereby, as the awning frame is raised, the auxiliary frame will rock to a vertical position and will fold the sheet 100 of fabric.

3. An awning comprising an awning frame pivotally mounted at the sides of an opening which is to be shaded, an auxiliary frame carried by the awning frame and arranged 105 to rock thereon, said auxiliary frame having weighted portions depending from the awning frame, a sheet of fabric provided with suspension means at its upper end and having a lower end portion disposed about the engaging portion of the awning frame and the auxiliary frame whereby the upper portion of the auxiliary frame will bear against the underside of the sheet of fabric, and detachable fasteners holding opposed portions 110 of the sheet together above the engaged portions of the awning frame and the auxiliary frame.

4. An awning comprising a sheet of material provided with suspension means at its upper end, an awning frame connected with the lower end portion of the sheet of material and having its ends pivotally mounted at the sides of an opening which is to be shaded, handles having lost motion connections with the ends of the awning frame, and means for locking the awning frame in its raised or lowered position.

5. An awning comprising a sheet of fabric provided with suspension means at its upper

- end, an awning frame engaged with the lower end portion of the sheet of fabric and having its ends pivotally mounted at the sides of an opening which is to be shaded, disks secured on the end portions of the frame and having circumferentially extending recesses with radial shoulders at the ends of the recesses, handle members mounted on the end portions of the awning frame and provided with studs engaging in said recesses and playing between said shoulders, and locking means co-operating with the handles and the side members of the awning frame.
6. An awning comprising a sheet of fabric provided with suspension devices at its upper end, an awning frame engaged with the lower end portion of the sheet of fabric and having its ends pivotally supported at the sides of an opening which is to be shaded, handles having lost motion connections with the ends of the awning frame, and locking plates to be engaged by the sides of the awning frame for holding the frame in raised position.
- 25 7. An awning comprising a sheet of fabric provided with suspension devices at its upper end, an awning frame engaged with the lower end portion of the sheet of fabric and having its ends pivotally supported at the sides of an opening which is to be shaded, handles having lost motion connections with the ends of the awning frame, and means co-operating with the handles for holding the same in the raised or lowered positions.
- 35 In testimony whereof I affix my signature.

ALBERT T. McCANLIS. [L. S.]
